UNITED STATES PATENT OFFICE.

EDWARD O. CARVIN AND LEMUEL C. BOURLAND, OF VALLEY SPRINGS,
CALIFORNIA.

HOLDER AND GUIDE FOR SCREWS.

SPECIFICATION forming part of Letters Patent No. 643,040, dated February 6, 1900.

Application filed September 23, 1898. Serial No. 691,727. (No model.)

To all whom it may concern:

Be it known that we, EDWARD O. CARVIN and LEMUEL C. BOURLAND, citizens of the United States, residing at Valley Springs, in the county of Calaveras and State of California, have invented certain new and useful Improvements in Holders and Guides for Screws, &c.; and we do hereby declare the following to be a full, clear, and exact description of the invention, such as will enable others skilled in the art to which it appertains to make and use the same.

This invention relates to holders and guides for screws, drills, and the like; and it consists of the construction and arrangement of parts more fully hereinafter described and claimed.

The object of the invention is to provide an improved construction of attachment adapted for use with a brace or other kindred device for holding a screw during the operation of insertion of a drill and avoid the necessity of hand manipulation, and consequently attain a better result.

In the accompanying drawings, Figure 1 is a perspective view of the improved device shown as holding a screw. Fig. 2 is a similar view of the device with a drill arranged therein. Fig. 3 is a section through the improved holder.

Referring to the drawings, wherein similar numerals are employed to indicate corresponding parts in the several views, the numeral 1 designates an elongated holder constructed of suitable metal and having its lower end or head cut through vertically, as at 2, to form opposite jaws 3. The said jaws have on their inner opposing faces a portion 4 of an angular opening which is completed by the two jaws coming together, and from the said jaws opposite slightly-bowed side arms 5 extend upwardly to a solid upper end or head 6, having an aperture 7 therein. The side arms 5 form springs for the jaws 3, and the holder is open, so as to give access to a stem 8, which is rotatably and slidably mounted in the end 6. The bowed side arms decrease gradually in thickness from their ends toward their central portions, where they are thinnest, so as to increase their spring action and adapt the jaws to open readily under pressure to admit of the passage of the stem therethrough in

driving a screw in the manner hereinafter described. The said stem has an upper angular end 9 for engagement with a brace or other analogous device, and at the lower end of 55 said stem a screw-driver end 10 is constructed by reducing or flattening the metal at this point by any suitable means. Immediately above the screw-driver end 10 a circumferential shoulder 11 is also formed on the stem, 60 and between the said shoulder and the upper end 6 and surrounding the stem is a coil-spring 12, which normally impels the said stem downwardly and holds the lower screw-driver end in engagement with the device held 65 by the jaws 3.

In Fig. 2 a drill is shown applied to the holder and guide and comprises a drill end 13 of any suitable form, with an angular upper body 14, provided with a notched or slotted 70 head 15. The body 14 is fitted in the angular opening partially located in each of the jaws 3, and the head 15 is held within the open portion of the holder and guide for engagement with the lower screw-driver end 10 75 of the stem 8.

In operation the jaws 3 are spread apart and the screw placed in position therein, as shown by Fig. 1, with the lower screw-driver end 10 of the stem 8 in the slot of the head of 80 said screw. The holder 1 is then held by one hand and the stem rotated and a downward pressure applied thereto by the other hand and the exposed threaded portion of the shank of the screw driven into the woodwork or material until the outer ends of the jaws bear 85 against said woodwork or material. The jaws will then open under the pressure of the stem, and the screw and stem will pass down between the jaws, so that the screw will be 90 held and guided during the entire operation of driving it and the entire driving operation made continuous or uninterrupted. The shoulder 11 is adapted to abut against the inner ends of the jaws to prevent the stem 95 from being projected through the jaws beyond a predetermined distance, and the diameter of the head of the screw is such that the jaws will be held apart when said stem enters between them a sufficient distance to relieve the 100 screw-threads from pressure. After the screw is seated the stem will be drawn upwardly

through the jaws and rearranged for further similar use. By adapting the jaws to open under the pressure of the stem and the latter to follow the screw through said jaws we are enabled to dispense with the use of auxiliary expanding devices, and the holder is adapted to be employed as a handle which may be held against the woodwork to steady the tool without danger of cutting or marring the woodwork.

In using a drill with the device a body 14, as set forth, is held by the jaws and a substantially-similar operation is carried on.

In Fig. 4 a modification is shown, and there-
15 in the shoulder 11 is dispensed with and an opening 16 formed in the lower bent end 17 of the spring 12 is removably fitted, thereby permitting a stem having thereon one kind of tool to be removed and another with a dif-
20 ferent tool to be substituted therefor.

The proportions and dimensions of the sev-
eral parts can be varied at will, and the mi-
nor details of construction can be changed
without in the least departing from the na-
ture or spirit of the invention.

Having thus described the invention, what
is claimed as new is—

In a holder and guide for screws, &c., the
combination of a non-rotatable holder and
30 guide member serving as a handpiece adapted
to be held to steady the tool during the entire
operation of driving the screw, and consist-

ing, essentially, of an upper guide-head, lower
jaws adapted to receive and clamp the head
and unthreaded portion of the shank of the 35
screw and hold and guide said screw during
the entire operation of driving the same, and
outwardly-bowed comparatively-free resil-
ient arms connecting the head and jaws, said
arms being gradually reduced in thickness 40
from said head and jaws toward their centers
to increase their spring action and adapt the
lower ends thereof to readily spread apart
and the jaws to open under the pressure
applied directly against the inner ends of 45
said jaws, a stem slidably and rotatably
mounted in the upper guide-head of the holder
and having a lower screw-driver end adapted
to force open the jaws and follow the screw
therethrough, an impelling-spring surround-
50 ing the stem and bearing at its upper end
against the guide-head of the holder, and a
fixed shoulder on the stem adapted to confine
the spring and also to abut against the inner
ends of the jaws to limit the movement of the 55
stem therethrough, substantially as shown
and described.

In testimony whereof we affix our signa-
tures in presence of two witnesses.

EDWARD O. CARVIN.
LEMUEL C. BOURLAND.
